CLAIM

The ornamental design for a charging device, as shown and described.

DESCRIPTION

FIG. 1 is an enlarged, front perspective view of a charging device in accordance with the disclosure.

FIG. 2 is an enlarged, front plan view of the charging device shown in FIG. 1.

FIG. 3 is an enlarged, rear plan view of the charging device shown in FIG. 1.

FIG. 4 is a top plan view of the charging device shown in FIG. 1.

FIG. 5 is a bottom plan view of the charging device shown in FIG. 1.

FIG. 6 is a left plan view of the charging device shown in FIG. 1.

FIG. 7 is a right plan view of the charging device shown in FIG. 1; and,

FIG. 8 is an enlarged detail view of a portion of the left plan view of the charging device shown in FIG. 6.

The broken lines shown in the figures form no part of the claimed design.

1 Claim, 8 Drawing Sheets
